Primary Examiner—A. Hugo Word*Assistant Examiner*—Ian Simmons*Attorney, Agent, or Firm*—Margaret L. Geringer**[57]****CLAIM**

The ornamental design for a stem driver instrument for a femoral hip prosthesis, as shown and described.

DESCRIPTION

FIG. 1 is a front perspective view of a stem driver instrument for a femoral hip prosthesis;
 FIG. 2 is a rear elevational view thereof;
 FIG. 3 is a side elevational view thereof;
 FIG. 4 is a side elevational view thereof of the side opposite the side shown in FIG. 3;
 FIG. 5 is a top plan view thereof;
 FIG. 6 is a bottom plan view thereof; and,
 FIG. 7 is a front elevational view thereof, opposite to the rear elevational view shown in FIG. 2.
